UNITED STATES PATENT OFFICE

141,416

DESIGN FOR A FILING MACHINE

Daniel J. Williams, Fairfield, and Ernst J. Tomek,
Danbury, Conn.; said Tomek assignor to said
Williams

Application July 31, 1944, Serial No. 114,660

Term of patent 14 years

(Cl. D37—1)

To all whom it may concern:

Be it known that we, Daniel J. Williams and Ernst J. Tomek, citizens of the United States, residing at Fairfield and Danbury, respectively, both in the county of Fairfield and State of Connecticut, have invented a new, original, and ornamental Design for a Filing Machine, of which the following is a specification, reference being had to the accompanying drawings forming part thereof.

Fig. 1 is a perspective view of a filing machine showing our new design; and

Fig. 2 is a side elevational view taken as looking from the far side of Fig. 1.

We claim:

The ornamental design for a filing machine, substantially as shown.

DANIEL J. WILLIAMS.
ERNST J. TOMEK.
